Primary Examiner—Louis S. Zarfus*Assistant Examiner*—L. Simmons*Attorney, Agent, or Firm*—Joseph H. Roediger**[57] CLAIM**

The ornamental design for a portable oxygen regulator for home use, as shown and described.

DESCRIPTION

FIG. 1 is a perspective view of a portable oxygen regulator for home use showing my new design;

FIG. 2 is a top plan view thereof;

FIG. 3 is a right side elevational view thereof, the left side being a mirror image;

FIG. 4 is a bottom plan view thereof;

FIG. 5 is a front elevational view thereof;

FIG. 6 is a rear elevational view thereof;

FIG. 7 is a perspective view of a second embodiment of a portable oxygen regulator for home use showing my new design;

FIG. 8 is a top plan view thereof;

FIG. 9 is a right side elevational view thereof, the left side being a mirror image;

FIG. 10 is a bottom plan view thereof;

FIG. 11 is a rear elevational view thereof;

FIG. 12 is a front elevational view thereof;

FIG. 13 is a perspective view of a third embodiment of a portable oxygen regulator for home use showing my new design;

FIG. 14 is a top plan view thereof;

FIG. 15 is a right side elevational view thereof, the left side being a mirror image;

FIG. 16 is a bottom plan view thereof;

FIG. 17 is a rear elevational view thereof; and,

FIG. 18 is a front elevational view thereof.
